DESIGN FOR A HAT

Morris Baum, New York, N. Y.

Application September 12, 1947, Serial No. 141,360

Term of patent 3½ years

(Cl. D3—13)

To all whom it may concern:

Be it known that I, Morris Baum, a citizen of the United States, residing at New York, in the county of New York and State of New York, have invented a new, original, and ornamental Design for a Hat, of which the following is a specification, reference being had to the accompanying drawing, forming a part thereof.

In the drawing:

Fig. 1 is a top plan view of a hat, showing my new design;

Fig. 2 is a front elevational view of the same; and

Fig. 3 is a vertical sectional view taken on the line 3—3 of Fig. 1.

I claim:

The ornamental design for a hat, as shown.

MORRIS BAUM.
